UNITED STATES PATENT OFFICE.

MAURICE E. BATES, OF KANSAS CITY, MISSOURI, ASSIGNOR TO BENJAMIN ELECTRIC MANUFACTURING COMPANY, OF CHICAGO, ILLINOIS, A CORPORATION OF ILLINOIS.

DESIGN FOR AN ELECTRIC-LIGHT SHADE.

No. 37,762.

Specification for Design.

Patented Dec. 26, 1905.

Application filed October 12, 1905. Serial No. 282,523. Term of patent 14 years.

To all whom it may concern:

Be it known that I, MAURICE E. BATES, a citizen of the United States, residing at Kansas City, in the county of Jackson and State of Missouri, have invented a new, original, and ornamental Design for Electric-Light Shades, of which the following is a specification, reference being had to the accompanying drawings, forming a part thereof.

In said drawings, Figure 1 shows a perspec-

tive view, and Fig. 2 shows a bottom plan view, of my design for electric-light shades.

I claim—

The ornamental design for an electric-light shade, as shown.

MAURICE E. BATES.
